COMBINATION HULLING AND ROLLING MACHINE

John K. Roskamp, Cedar Falls, Iowa

Application September 28, 1950, Serial No. 187,213

6 Claims. (Cl. 99—237)

1

This invention relates to oat hullers in general and more specifically to a single unit combining both hulling and rolling operations whereby the oats are not only hulled but also flake rolled in a single operation.

Heretofore known machines have been used for hulling the green oats and a separate machine in a separate operation was required in order to roll the oats. Such machines necessitated a large initial investment and also required a large amount of space in order to accommodate the machines. When separate machines were used for hulling and flaking, an additional elevating mechanism was also usually required.

An object of the present invention is to provide a single machine incorporating both operations and which requires a small amount of floor space in contradistinction to previously known devices.

Another object of the present invention is to provide a combination huller and flaker in which the huller is mounted directly on the flaker and in which the hulled oats are discharged directly into the flaking roll.

A further object of the invention is to provide a combination unit in which the flaking rolls may be rendered inoperative or varied to give different size flakes as required without affecting the hulling operation.

Still a further object of the present invention is to provide a complete unit which will hull the oats, separate the hulls, dispose of the hulls and roll the oats to desired size in a single unit whereby additional equipment is unnecessary.

With the above and other objects in view which will appear as the description proceeds, my invention consists in the novel features herein set forth, illustrated in the accompanying drawings and more particularly pointed out in the appended claims.

Referring to the drawings in which numerals of like character designate similar parts throughout the several views:

Figure 1 is a perspective view of the machine of the present invention;

Figure 2 is an end elevational view partially broken away;

Figure 3 is a longitudinal sectional view of the device taken on line 3—3 of Fig. 4; and

Figure 4 is a lateral sectional view through the machine taken on line 4—4 of Fig. 3.

In the drawings the entire combined unit is depicted in Figure 1 and generally comprises a hulling unit 10 and a rolling unit 11. The hulling unit is superimposed on the rolling unit and the hulled oats pass directly from the hulling unit into flaking rolls and thence the groats are re-

moved while the hulls are discharged and those oats not hulled are returned to the hulling unit.

A hopper 12 is provided on the device into which the green oats are fed and they pass into the tube 13. A screw conveyor 14 in tube 13 is rotatably journaled in ball bearings and raises the oats through a bearing box 15 into the hulling chamber 16. Through the chamber 16 there extends a shaft 17 which is journaled in three double row flange ball bearings 18. Rotation of the shaft 17 is effected by means of pulley sheave 19 with which a drive belt, not shown, cooperates in association with a source of power of any desired type.

The hulling chamber 16 has a hulling head cap 20 which is bolted onto the hulling head or hulling chamber and which is also secured to the bearing box. In the top of tube 13 there is an opening through which the oats raised by conveyor 14 pass into bearing box 15. There is also an opening 21 in the center of the head cap 20 through which the oats pass into the hulling chamber 16. The conveyor 14 extends only to the bottom of the bearing box 15 as seen in Figure 3 of the drawings.

Secured to shaft 17 in the hulling chamber 16 are two discs 22 and 23 having projections 24 thereon of rounded configuration adapted to provide a rolling action to the oats. An adjustable cylinder 25 is provided in the hulling chamber 16 which by means of handle 26 can be rotated. This cylinder 25 is corrugated thus forming a series of projections 27 on the inner face thereof which extend into the chamber 16. On the external surface of the chamber 16 a tapered slot through which a bolt is secured to handle 26 and to cylinder 25, extends. When handle 26 is slightly moved the cylinder 25 is axially moved in relation to disc 22 and the space between the projections 27 and 24 is consequently varied to suit the size of oats to be hulled for apparent reasons. The discs 22 and 23 in conjunction with cylinder 25 constitute the hulling surfaces or discs.

A center piece 28 is provided for supporting the center bearing 18. This center piece 28 has an opening therethrough between the hulling chamber 16 and the remainder of the unit 10.

A screw conveyor 29 is rotatably journaled in the device and is operated by means of pulley 30 and pulley 31 on shaft 17 with belts 32 or the like therebetween. The conveyor extends between the two end frames of the machine and through the opening in center piece 28 for conveying the oats therefrom after having been subjected to a hulling operation in chamber 16.

55 A fan 33 is mounted on shaft 17 for rotation

therewith and this fan creates an air draft on the hulled oats passing along conveyor 29 which draws the hulls from the grain and blows them into a hull bin.

The grain from which the hulls have been partially removed at this point fall into the Carter disc separating chamber 34. In this chamber a plurality of Carter discs 35 on shaft 36 mechanically separate the groats from the remaining hulls and whole oats which have not been completely hulled the first time through the hulling head or chamber 16. Each of the Carter discs 35 has three spokes 37 (Figure 4) on each of which are mounted square pieces of sheet metal 38 which are bent to serve as an auger for conveying grain in the chamber 34 back into conveyor 14. An opening 39 is provided for the return of the grain into conveyor 14 from chamber 34 by the pieces 38. The connection between chamber 34 and conveyor 14 from opening 39 is seen in dotted lines at 103 in Fig. 3. In this manner the un-hulled oats are returned through the hulling chamber 16 a second time.

The Carter disc, as is well known, is a circular member having a large number of pockets on each side thereof of approximately the exact size of an oat groat. When the disc is rotated each of the pockets become filled with an oat groat or hull lying in the bottom of the separating chamber. When a pocket rises into the air stream above the pool the air picks off the hull. The centrifugal action retains the groat in the pocket until it travels approximately 270° from the lower vertical. At this point the groat leaves the pocket and is thrown onto a baffle plate 40 below which are mounted the rolls as will be explained herein-after. The baffle plate 40 can be used for directing the hulled oats into the rollers 46 or outside of the rolling mechanism. This baffle plate enables the operator to obtain hulled and flaked oats or merely hulled oats. When the grain is hulled only, the rollers can be shut off and the flaking unit is idle. The Carter discs 35 mounted on shaft 36 are driven by a continuous roller chain 66 (Figure 2) from a sprocket on the shaft on which conveyor 29 is mounted.

In order to control the flow of air to fan 33, an air damper 104 is provided which is pivotally mounted and biased to contact with stationary member 105 by spring 41. A handle on the outside of the device rotates the rod 42 which pushes the damper 41 forward or backward over the discs 35. The baffle operates on the principle that, providing the volume of air remains constant, the smaller the aperture the greater will be the speed of the air.

Also connected to the handle for operating the damper 41, is another rod, not shown, which swivels a baffle plate 43. This baffle plate 43 directs the grain to a more vertical fall over the discs 35 when the air damper 41 is adjusted forward for greater severity, or speed of the air. An air damper 44 opens or closes an opening 45 to control the amount of air taken in to the fan 33 from this side.

Rollers 46 are rotatably mounted on shafts 47 which protrude through bearing housings 48 on each side of frame 49 for securing thereto of drive sheaves, not shown. The bearing housings 48 on the back roll are fastened to the frame 49 by means of cap screws 50. The bearings inside the housing are not shown. They are double row, self aligning, sleeve type bearings. On the front roll the housings are movable in and out with respect to the back roll. A flange 51 of the

housing at the base slides in a channel made of two angle iron pieces, not shown.

An adjustable tension between the rollers is obtained from the following mechanism. Handles 52 are secured to threaded rods 53 which apply tension against a cast iron block 54 mounted on a shaft 55 on the inside of each channel iron.

This shaft has a cam 56 on each end thereof secured with a key or the like. Behind the cams 10 are three spring leaves 57. These spring leaves are held by cams 56 on the bottom and by angle irons 58 secured to the frame at the top. Pressure is applied in the middle to a knob 59 formed in the center of housing 48. Rapid tensioning and release can be applied to the rolls 46 by a handle 100 secured to the center of shaft 55 for rotating the same and the cam 56 to move the housing 48 by means of knobs 59. When proper tension has been obtained between the rollers 20 as set forth above under operation conditions, a lock nut 60 is tightened against the frame 49 to prevent the handles 52 from getting loose and turning.

On each side of the rollers 46 between the 25 channel iron frame 49, two pieces of sheet metal can be provided to contain and direct the flow of the oat flakes. At the bottom of the machine is an opening from which the finished product is obtained.

The conveyor member 14 is on a feeder shaft 61 driven by sheave 62 through belts 63 and sheave 64 on idler shaft 65 to the drive feeder. (Figure 1.) Shaft 65 is driven by the continuous 35 roller chain 66 from the shaft of screw conveyor 29 which also drives shaft 36 having the Carter discs.

Beneath bearing box 15 is a box 67 and in the bottom of the bearing box is an opening into the box 67. This box 67 is hinged on the bearing box and covers the opening therein, to collect stones and other non-magnetic material which cannot be drawn off with a magnet as usually applied to a device of this character.

In Figures 3 and 4 of the drawings the arrows indicate the flow of air and the passage of the green oats through the huller and roller to the outlet opening for the finished product and these, when taken together with the foregoing detailed description of the invention, will render the operation of the device clear.

The end result of the present device is a completely finished product resulting from a continuous process in a single machine which has not heretofore been possible and it is this combination which broadly constitutes the present invention. It is apparent that minor changes in details of construction of the device can be effected without departing from the scope of the present invention as defined in the appended claims.

I claim:

1. A device for sequentially and continuously completely hulling, separating and flaking grain comprising in combination, a grain huller and a flaking mechanism for the hulled grain, means for feeding grain to said huller, means for mechanically and continuously moving hulled grain from said huller to said flaking mechanism, means for removing hulls from the grain intermediate said huller and said flaking mechanism, and means associated with said removing means for returning unhulled or partially hulled grain to said huller, and means between said hull removing means and said flaking mechanism operable into alternative selective positions for selec-

tively directing hulled grain into said flaking mechanism or outside said device in unflaked condition.

2. A device for treating grain comprising a huller, mechanical feed means for removing grain from said huller, hull and grain separating means, return means for unhulled or partially hulled grain between said separating means and said huller and flaking means associated with and opening into said separating means for directly receiving and rolling completely hulled grain and a plate between said separating means and said flaking means rotatable into two positions, one for directing hulled grain into said flaking means directly from said separating means and the other for directing hulled grain outside of said device in unflaked condition.

3. A device for treating grain as claimed in claim 2, and a screw conveyor opening into said huller for continuous insertion therein of untreated grain, said mechanical feed means for removing grain from said huller comprising a screw conveyor entering into the discharge end of said huller and extending to and over said hull and grain separating means.

4. A device for treating grain as claimed in claim 2, said hull and grain separating means comprising a plurality of rotatably mounted discs having numerous grain receiving pockets in the lateral faces thereof, shaped plates on said discs in proximity to the periphery thereof, said plates upon rotation of said discs being adapted to direct unhulled or partially hulled grain back into said huller for retreatment thereof.

5. A device for treating grain as claimed in claim 4 and including air inlet means to said separating means, and air draft control means for varying the intensity of air to said separating means.

6. A device for treating grain as claimed in claim 2, said flaking means comprising two rotatably mounted coating rollers positioned directly below and open to said hull and grain separating means and adapted to receive directly therefrom hulled grain for flaking, one said roller being movable toward and away from the other of said rollers for varying the pressure therebetween and for rendering said rollers inoperative.
